ATTORNEY.

UNITED STATES PATENT OFFICE.

HOARD LEE, OF SHREVEPORT, LOUISIANA.

DESIGN FOR A MOTOR-VEHICLE STEERING-WHEEL.

58,244.

Specification for Design. Patented June 28, 1921.

Application filed March 21, 1921. Serial No. 454,299. Term of patent 14 years.

To all whom it may concern:

Be it known that I, HOARD LEE, a citizen of the United States, residing at Shreveport, in the parish of Caddo, State of Louisiana, have invented a new, original, and ornamental Design for a Motor-Vehicle Steering-Wheel, of which the following is a specification, reference being had to the accompanying drawing, forming part thereof.

The figure is a plan view of a steering wheel, showing my new design.

I claim:

The ornamental design for a motor vehicle steering wheel as shown.

HOARD LEE.

Witnesses:

R. M. SMITH,
E. V. HARDWAY.
